Upland, Ind.

Application December 29, 1953, Serial No. 28,261

Term of patent 14 years

(Cl. D33—14)

To all whom it may concern:

Be it known that we, William B. French and John W. Bragg, citizens of the United States, residing at Fairmont and Upland, respectively, in the county of Grant and State of Indiana, have invented an ornamental Design for a Table, of which the following is a specification, reference being had to the accompanying drawing, forming a part thereof.

Fig. 1 is a perspective view showing our new design for a table;

Fig. 2 is a side elevation thereof, viewed from the left of Fig. 1;

Fig. 3 is a side elevation thereof, viewed from the right of Fig. 1; and

Fig. 4 is a top plan view with a portion of the bottom omitted for convenience of illustration.

We claim:

The ornamental design for a table, as shown.
